WILLIAM A. SMITH, OF PHILLIPSBURG, NEW JERSEY, ASSIGNOR TO INGERSOLL-RAND COMPANY, OF JERSEY CITY, NEW JERSEY, A CORPORATION OF NEW JERSEY.

AUTOMATIC AIR-FEED CONTROL FOR ROCK DRILLS.

1,415,958.

Specification of Letters Patent.

Patented May 16, 1922.

Application filed February 25, 1921. Serial No. 447,757.

To all whom it may concern:

Be it known that I, WILLIAM A. SMITH, a citizen of the United States, and a resident of Phillipsburg, county of Warren, State of

5 New Jersey, have invented a certain Automatic Air-Feed Control for Rock Drills, of which the following is a specification.

This invention relates to fluid pressure rock drills of the hammer type, but more 10 particularly to automatic air feed control for the feeding element which advances the machine. The invention is especially applicable to a stope drill, although it may advantageously be used in connection with 15 drifters and other types of rock drills for drilling substantially horizontal and down holes, whether or not the machine is provided with an independent rotation motor, rifle bar rotation or other automatic rotation.

20 In operating a stope drill for instance, which may be taken as an illustrative example, if a soft spot is encountered the power of the air feed should ordinarily be reduced, 25 but full rotation and hammer power should be retained, or if possible, increased rotation should be produced, to enable the machine to operate in the most efficient manner.

These changes in the air feed control have 30 heretofore been effected by hand and to suit the conditions of the work, and one object of the present invention is to enable the air feeding element to be automatically controlled substantially without hand regulation 35 after the drilling is started.

Another object is to effect such control by 40 automatic means responsive to the resistance to the rotation and torque of the rotation motor for automatically varying the pressure in the air feed cylinder of the air feed- 45 ing element.

In accordance with my invention, I have 45 devised automatic means preferably directly responsive to or affected by the torque of the rotation motor through the agency of mechanical devices for controlling the pressure in the air feed.

Automatic regulation and control of the air feed renders the machine more sensitive 50 to drilling conditions than can be obtained with hand control and the machine will respond automatically to the requirements more quickly than with hand control. This tends to avoid sticking, but if the steel does 55 stick, my automatic devices have been found

to quickly free the steel in cases where the steel cannot be freed by manual adjustments of the motor and air feed, because the automatic devices have proved to be more effective and better adapt the machine to its work than human agencies.

Since the operator is not required to keep one hand on the rotation handle, nor adjust controlling valves to control the air feed, he may stand aside, in using a stope drill for 65 instance, and he is not subjected to the annoyances and discomfort of dripping sludge and cleaning water in the case of wet drilling, which is a material advantage for the operator.

70 Further objects of the invention will hereinafter appear and the invention is illustrated in one of its preferred forms in the accompanying drawings in which—

Figure 1 is a side elevation, partly in vertical section of a stope drill illustrating the invention;

75 Figure 2 is a detail diagrammatic horizontal sectional view through the rotation motor on the line 2—2 of Figure 1;

80 Figure 3 is a detail horizontal sectional view through the air feed controlling valve on the line 3—3 of Figure 1 looking in the direction of the arrows with the air feed relief valve closed;

85 Figure 4 is a view similar to Figure 3 with the air feed relief valve open;

90 Figure 5 is a detail horizontal sectional view through the air feed cylinder on the line 5—5 of Figure 1; and

95 Figure 6 is a detail horizontal sectional view similar to Figure 3 showing a modification of the air feed controlling or relief valve.

100 Referring to the drawings, a stope drill is illustrated in the figures having the cylinder A and front head B provided with the rotation sleeve C through which the drill steel D extends in position to receive the impact blows of the hammer E. An independent fluid actuated rotation motor is shown in this instance for rotating the drill steel, a gear motor being indicated having the gears F, only one of which is shown in Figure 1, in the motor casing formed by the back end portion G of the cylinder. The head block G' is shown located between the cylinder portion G and the feed cylinder head G² of the fluid pressure feed cylinder H having the piston J and hollow piston rod K pivoted to the 110

foot L provided with a plurality of rock engaging points L' for preventing rotation of the piston and piston rod. One of the gears F of the motor is operatively connected 5 through a suitable shaft O and pinion P meshing with the gear Q on the rotation sleeve C for rotating the drill steel. The cylinder A, back end portion or motor casting G, head block G', feed cylinder head G² 10 and feed cylinder H, are adapted to be held together by any suitable means as through bolts R.

The piston rod K forms a stationary non-rotatable member of the feeding element, 15 and cylinder H forms a longitudinally movable rotatable element upon which the rock drill is mounted. A guide rod S having a longitudinal groove T is longitudinally movable within the piston rod K but held from 20 rotation by suitable means shown as a key U lying in the groove T and held in a sleeve V suitably connected to the piston rod. The guide rod S is provided with a guide rod head W held within the feed cylinder head 25 G² by the internally tapered bearing sleeve X. A retaining spring Y on the piston rod sleeve V is adapted to engage the tapered bore of the bearing sleeve X and hold the cylinder H in retracted position when the 30 machine is not in use.

The feed cylinder head G² is conveniently provided with a valve casing Z having a feed cylinder relief valve a movable therein, controlling the relief passage b opening to the 35 atmosphere at the port c. The valve casing is provided with the removable cap d beneath which is a coiled spring e which normally maintains the valve in closed position as indicated in Figure 3, closing the relief 40 or exhaust passage from the air feed cylinder. The valve is preferably provided with the longitudinal passage f to prevent the building up of pressure behind the valve.

As shown, there is a clearance space g between the periphery of the guide rod head W and the interior of the feed cylinder head G², and the guide rod head is also provided with the port h for admitting pressure to the feed cylinder and for relieving pressure 50 from the feed cylinder. The inner end j of the valve a bears against a cut away portion k of the guide rod head W, and as the guide rod T and guide rod head W are held against rotation, although capable of 55 longitudinal movement, the guide rod head W forms an abutment against which the spring pressed air feed relief valve a bears, and rotation of the feed cylinder H and feed cylinder head G² relatively to the guide 60 rod T and piston rod K in the direction of the arrows o in Figures 3 and 4, and tends to open the relief valve a to a larger or greater extent depending upon the resistance to rotation of the drill steel.

65 In the operation of the devices fluid pres-

sure is supplied to the machine through the usual hose connection p controlled by the throttle q in the head block G' and the fluid supply passes through the passage r in the head block and the port s in the feed 70 cylinder head G² to the space within said head and thence through the port h to the feed cylinder. The machine will be advanced to its work until the resistance to rotation is sufficient to cause the feed cylinder H to rotate or turn in the direction opposed to rotation with sufficient force to vary the leverage and open the relief valve a and relieve the pressure in the air feed cylinder. As soon as the resistance decreases 80 sufficiently, the air feed relief valve a automatically closes and full feeding is resumed. This operation continues automatically until the drilling is stopped.

In the modification shown in Figure 6, the feed cylinder head G³ is provided with a valve casing t having a valve u provided with a head v subjected to live air through the port w and passage x tending to hold the valve in closed position. In this case 90 live air is substituted for the spring e and a vent y is provided in the valve casing t beneath the head v. Otherwise, the operation of the valve is the same as described in connection with the other figures. 95

I claim:

1. In a rock drill of the hammer type, the combination with the drill cylinder, of means for rotating the drill steel, a feeding element for feeding the machine forward, comprising a stationary non-rotatable member; a rotatable and longitudinally movable member connected to the drill cylinder, means for limiting the rotary movement of said longitudinally movable member, and means actuated by said rotary movement for automatically controlling said fluid pressure feeding element in accordance with the resistance to rotation.

2. In a rock drill of the hammer type, the combination with the drill cylinder, of an independent motor for rotating the drill steel, a fluid pressure feeding element for feeding the machine forward, comprising a stationary non-rotatable member, a rotatable and longitudinally movable member, connected to the drill cylinder, means for limiting the rotary movement of said longitudinally movable member, and means actuated by said rotary movement for automatically controlling said fluid pressure feeding element in accordance with the torque of the motor.

3. In a rock drill of the hammer type, the combination with the drill cylinder, of means for rotating the drill steel, a feeding element for feeding the machine forward, comprising a stationary non-rotatable member, a rotatable and longitudinally movable member connected to the drill cylinder, 125

means for limiting the rotary movement of said longitudinally movable member, and a valve actuated by said rotary movement for automatically controlling said fluid pressure feeding element in accordance with the resistance to rotation.

4. In a rock drill of the hammer type, the combination with the drill cylinder, of an independent motor for rotating the drill steel, a fluid pressure feeding element for feeding the machine forward, comprising a stationary non-rotatable member, a rotat-

able and longitudinally movable member connected to the drill cylinder, means for limiting the rotary movement of said longitudinally movable member, and a valve actuated by said rotary movement for automatically controlling said fluid pressure feeding element in accordance with the torque of the motor.

In testimony whereof I have signed this specification.

WILLIAM A. SMITH.
